UNITED STATES PATENT OFFICE

2,493,167

FILING APPARATUS

Richard P. Scholfield, New York, N. Y., assignor
to Wheeldex Manufacturing Co., Inc., a corpo-
ration of New York

Application July 11, 1946, Serial No. 682,949

15 Claims. (Cl. 129—16)

1

The present invention relates to rotary filing equipment of the type wherein a plurality of filing cards are removably secured upon the periphery of a filing drum, for ready access for inspection or posting, by rotation of the drum, to bring selected cards quickly to a position adjacent the operator.

The invention has to do primarily with relatively small, portable rotary files adapted to be positioned upon a desk or table and to be moved from place to place as desired.

A primary object of the invention is to simplify constructions of this type, so that they may be manufactured at less cost and therefore distributed more widely, yet without sacrificing any of the advantages of more complicated and expensive filing devices heretofore in use.

A further object of the invention is to provide small rotary files of this type which are simpler, stronger, more long lasting, and less likely to get out of order than previous devices.

Another object of the invention is to provide a construction which particularly lends itself to manufacture by molding process, using plastic materials. To this end, the invention provides a construction consisting essentially of only three major molded parts, the other parts employed being standard articles of commerce, such as shafts, washers, nuts, screws and the like.

Thus, the invention aims to provide an improved rotary filing drum, of small to intermediate size, which is extremely simple in construction and which can be assembled in mass production with maximum ease from only a few specially molded parts.

The invention also incorporates a number of features covered by prior patents owned by the assignee of the present application, and in a number of respects, constitutes specific improvements thereon, namely Patents Nos. 2,046,655, July 7, 1936; 2,231,029, Feb. 11, 1941; Re. 22,765, June 21, 1946.

In the accompanying drawings, a specific embodiment of the invention is shown for purposes of illustration, but it must be understood that the invention is not limited to the details shown therein and described below.

In the drawings,

Figure 1 is a vertical section, partly in elevation showing a drum and one form of suitable supporting structure;

Figure 2 is an end elevation, with certain parts broken away, and with the support omitted, looking from the right of Figure 1;

2

Figure 3 is an axial section of the rim element shown in Figure 1;

Figure 4 is an end view looking from the left of Figure 3;

Figure 5 is an end view, taken from the right-hand end of Figure 1, with the drum head removed;

Figure 6 is a side elevation and sectional view of a modified form of axle and drum head;

Figure 7 is a side elevation of the modified axle, with a part broken away, and

Figure 8 is an elevation of a washer adapted for use with the modified axle.

The filing drum assembly of the present invention preferably comprises a stationary shaft 10 having a reduced portion 11 terminating at one end in a threaded end portion 12 and at the other in a radial shoulder 13. The ends of the shaft are drilled and tapped as at 14, 15, for the reception of screws 16, 17, extending through supporting end plates 18, 19, extending upwardly from a suitable base 20. A fibre spacing sleeve 19' may be employed, surrounding the shaft, between the adjacent drum head and the end member 19. It will be understood that the shaft 10 is supported against rotation by the screws or bolts 16, 17, which clamp the ends of the shaft to the supports 18 and 19.

The filing drum comprises only four major parts, two of which are identical, i. e., drum head members 21, 22, a rim member 23 and a clutch and brake core 24. Each of the identical drum heads comprises a central aperture 25, a central, outwardly projecting annular disk or web 26, a cylindrical shouldered portion 27 and a radially extending peripheral flange 28. As noted above, each of these head members is adapted to be made of molded plastic material, and one set of dies will suffice for the production of both.

The rim 23 comprises a cylindrical portion 30 having a card retaining rail 31 formed integrally therewith, projecting outwardly therefrom and extending circumferentially around the same. The rail, including its attaching web and rail head, may have a cross-sectional shape of the kind shown and described in my prior patent, Re. 22,765, June 21, 1946.

The rim also is provided with an integral, circumferentially extending, inwardly projecting ring 32 having formed therein a plurality of radial, outwardly projecting pockets 33, closed at their inner ends by a flange 34 and open at their outer ends. It should be noted that the flange 34 extends inwardly beyond the inner diameter 35 of the ring 32.

A suitable number of axially extending enlargements or ribs 36, 37 and 38, formed integrally with the rim, extend from the ring 32 or flange 34, toward the opposite end of the rim, but terminate a distance therefrom equal to the distance between the outer face of the ring 32 and the adjacent end of the rim.

As noted in Figure 1, the end portions 40, 41 of the rim, projecting axially beyond the ribs 36-38 and the ring 32 are the same length as, and snugly fit upon, the shouldered portion 27 of each drum head. The latter are secured in place by suitable screws 42, extending through countersunk holes in the drum head, into the ends of the enlargements 36-38 and into the circumferential rib 32, in the spaces between the pockets 33.

The clutch core 24 has an axial bore 45 corresponding to the diameter of the reduced portion 11 of the shaft 10, and is provided with an axially elongated hub 46, having an external diameter equal to the diameter of the non-reduced portion of the shaft 10, and equal to the diameter of the aperture 25 in the drum head members 21, 22.

The opposite end of the hub preferably abuts a friction washer 47 surrounding the reduced portion 11 of the shaft and lying against the radial shoulder 13. A knurled nut 48, threaded on the end portion 12 of the shaft applies endwise pressure to the hub and forces the same against the friction washer 47, backed up by the shoulder 13.

The periphery of the clutch core 24 is provided with a plurality of recesses, formed by inclined, flat portions 50, extending from the periphery 51 inwardly to curved bottoms 52 and radial shoulders 53. As shown in Figure 5, the periphery 51 of the clutch core has only a slight clearance with the inner circumference 35 of the inwardly projecting clutch ring 32. A roller 55 having a radius slightly less but substantially equal to the depth of each recess on the periphery of the clutch core is disposed in each of the pockets 33 in the clutch ring 32. These rollers may be made of steel, or preferably, of rubber, to provide quietness in operation and a soft touch.

Annular rings 57, 58 may be adhesively or otherwise secured to the end faces of the drum heads, serving the dual purpose of covering the countersunk screws 42 and acting as name plates, carrying trade marks, patent numbers and the like. The rings may be made of sheet metal or any other suitable material.

When the parts are assembled as indicated in Figure 1, the left hand drum head 22 is journalled for rotation on the non-reduced portion 10 of the shaft and the right hand drum head is journalled on the extended hub portion 46 of the clutch core 24. The parts are secured together as a unit by the aforementioned screws 42 and are restrained against axial movement on the shaft by the sleeve 19 and by the drum head 21, interposed between the clutch core 24 and the inner radial face of the nut 48. The desired frictional resistance to movement of the clutch core 24 may be effected by tightening or loosening the nut 48, free to travel on the threaded shaft section 12 between the support 18 and the extended hub 46 of the clutch core.

Referring to Figure 2, it must be understood that one or another of the recesses on the periphery of the clutch core will always be substantially at the top position. Hence, when the drum is rotated in a counterclockwise direction, Figures 2 and 5, the rollers 55 will ride up the inclined bottoms 50 of the uppermost recesses and will be carried around in the associated pockets 33 in

the inwardly projecting clutch ring 32, thus permitting free rotation of the drum in that direction, without imparting rotation to the clutch core 24. If an attempt is made to rotate the drum 5 in the opposite direction, however, the rollers will drop down into the bottom of the upper clutch core recesses, against the shoulders 53, and will 10 jam between those shoulders and the side walls or corners of the pockets 33, thus preventing rotation of the drum in the latter direction, unless the clutch core 24 is also rotated, against the resistance of the friction washer 47.

The modified form of axle shown in Figures 6 and 7 is preferred in some cases, for the sake of 15 economy, since it is of the same diameter from end to end, requires less metal, and does not have a reduced end portion. Instead, the axle 60 is of uniform diameter except for a circumferential channel 61, adapted to receive a C-shaped spring 20 washer 62, which may be snapped in place by passing the open side 63 thereof over the bottom of the channel 61. A brass washer 64 and a fiber washer 65 are backed up by the C-shaped washer 62 and take the place of the shoulder 13 and washer 47 in the first form of the invention.

The outer threaded end 66 of the axle 60 is provided with a milled out portion, leaving a flat surface 67 at the outer end thereof. A washer 68 having a D-shaped opening 69 is non-rotatably 30 mounted upon the end 66 of the shaft, with the flat portion 70 of the opening registering with the flat portion 67 of the shaft end. The washer 68 is of an overall diameter equal to the outside diameter of the hub 71 of the drum head 21. The interposition of this non-rotatable washer on the shaft between both the end face of the clutch core hub and the drum head hub and the knurled adjusting nut 72 prevents the transmission of 35 rotational forces from the clutch core or drum head to the nut, and thereby eliminates any possibility of the adjusted position of the nut being changed inadvertently. The washer 68 is preferably of an anti-friction material, so that it does not interfere with the rotation of the drum, the latter being controlled as previously described.

With an axle of the type shown in Figures 6 and 7, the drum head at the opposite end to the one shown will have a central hole of smaller diameter or, if desired, a separate ring may be 50 pressed into the larger central eye, to reduce its diameter and to make it correspond to the shaft diameter.

From the foregoing description, it will be seen that the present invention provides an improved, 55 extremely simple, inexpensive, readily manufactured and assembled filing drum, which may be rotated freely in one direction, but which is restrained against rotation in the opposite direction, in the absence of deliberate turning force in 60 that direction.

Although the invention has been described with considerable particularity in the foregoing specification, it must be understood that it is not limited to the details shown in the accompanying 65 drawings and described above, but covers all modifications coming within the scope of the appended claims and their equivalents.

I claim:

1. A rotary filing drum assembly comprising a 70 stationary shaft having a radial shoulder and a reduced portion adjacent thereto, a pair of spaced drum heads mounted for rotation coaxially of the shaft, a cylindrical rim carried by the heads and having a card retaining rail projecting 75 from its periphery, a clutch element in the space

between said heads on the reduced portion of the shaft, means frictionally restraining said element against rotation on said portion of the shaft, and an overrunning connection between said clutch element and the rim, permitting free rotation of the drum in one direction and frictionally restrained rotation in the other.

2. A rotary filing drum assembly comprising a stationary shaft, a pair of spaced drum heads mounted for rotation coaxially of the shaft, a cylindrical rim carried by the heads and having a card retaining rail projecting outwardly from its periphery, a clutch element mounted on and projecting outwardly from said shaft into close proximity to the inner surface of said rim, means for applying to an end face of said clutch element frictional resistance to rotation relative to the shaft, and an overrunning connection between the clutch element and the inner surface of the rim permitting free rotation of the drum in one direction and frictionally restrained rotation in the other.

3. A rotary filing drum assembly comprising a stationary shaft having a threaded section, a pair of spaced drum heads mounted for rotation coaxially of the shaft, a cylindrical rim carried by the heads and having a card retaining rail projecting outwardly from its periphery, a clutch element rotatably mounted on, restrained against axial movement with respect to, and projecting outwardly from said shaft into proximity to the inner surface of said rim, a nut on said threaded section of the shaft for applying to an end face of said clutch element frictional resistance to rotation relative to the shaft, and an overrunning connection between the clutch element and the inner surface of the rim permitting free rotation of the drum in one direction relative to said clutch element and frictionally restrained rotation in the other direction with said element.

4. A rotary filing drum assembly comprising a shaft non-rotatably supported at its ends, a pair of spaced, shouldered drum heads mounted for rotation coaxially of the shaft, a cylindrical rim carried by the shoulders of the heads, having an outwardly projecting, integral, card-retaining rail on its periphery and an inwardly projecting flange spaced from and adjacent to one of the drum heads, a clutch element held frictionally against rotation on the shaft and disposed within the space between the flange and the adjacent drum head, and overrunning clutch elements confined by the flange and the adjacent drum head, cooperating with the adjacent inner surface of the rim and said frictionally held clutch element, permitting free rotation of the drum in one direction and restrained rotation in the other.

5. A rotary filing drum assembly comprising a stationary shaft having a radial shoulder and a reduced end portion adjacent thereto, a clutch core on the reduced portion of the shaft having an elongated, axially projecting hub, means forcing the core against the shoulder and frictionally restraining the core against rotation on the shaft, a pair of drum heads one journaled on the shaft and the other on the hub extension, a cylindrical rim carried by the heads, having an outwardly projecting, circumferential card retaining rail and an inwardly projecting flange adjacent to but spaced from the latter drum head and partially enclosing said clutch core, and additional clutch means confined by the flange and the adjacent drum head establishing overrunning connection between the clutch element and

the inner surface of the rim, permitting free rotation of the drum in one direction and frictionally restrained rotation in the other.

6. A rotary filing drum assembly comprising a stationary shaft having a radial shoulder and a reduced portion adjacent thereto terminating in a threaded end portion, a clutch core on the reduced shaft portion having an elongated hub extending toward the threaded end portion and having an outside diameter equal to the non-reduced shaft diameter, a nut on the threaded portion adapted to apply axial force to the hub to restrain rotation thereof, a filing drum journaled on the shaft and hub extension, having an outwardly projecting card retaining rail upon its periphery and overrunning clutch elements associated with its interior surface cooperating with the clutch core, permitting free rotation of the drum in one direction and frictionally restrained rotation in the other direction.

7. A rotary filing drum assembly comprising a stationary shaft having a radial shoulder and a reduced portion adjacent thereto, terminating in a threaded end portion, a clutch core on the reduced shaft portion having an elongated hub extending toward the threaded end portion of an outside diameter equal to the non-reduced shaft diameter, a nut on the threaded portion adapted to apply axial force to the hub, friction producing means between the end of the hub and the shoulder, a pair of drum heads mounted on the shaft and hub extension, respectively, a cylindrical rim carried by the drum heads having an outwardly projecting card retaining rail and an inwardly projecting flange adjacent one end of said clutch core, and a plurality of rollers confined in the space between the flange and the adjacent drum head, establishing overrunning connection between the clutch core and the adjacent inner surface of the drum rim, permitting free rotation of the drum in one direction and frictionally restrained rotation in the other.

8. A rotary filing drum assembly comprising a stationary shaft having a radial shoulder and a reduced portion adjacent thereto terminating in a threaded end portion, a clutch core on the reduced shaft portion having an end face restrained against axial movement by said shoulder and an elongated hub extending toward the threaded end, a nut on the threaded shaft portion adapted to urge the core toward the shoulder, a cylindrical drum journaled at its ends upon the shaft and hub extension and having card retaining means on its periphery, said drum having upon its inner surface overrunning clutch means cooperating with said core, permitting free rotation of the drum relative to the core in one direction, but lacking the drum to the core upon rotation in the other direction.

9. A drum for use in a rotary file including a stationary shaft, said drum comprising two substantially identical one-piece drum heads each having a central annular disk portion, a cylindrical shouldered portion and a radial flange, and a one-piece, molded, plastic rim comprising a cylindrical body, an integral, circumferentially extending, outwardly projecting card retaining rail, and a plurality of integral inwardly projecting, axially extending ribs terminating in spaced relation from the ends of the cylindrical body, the ends of the body beyond the ribs being seated upon said cylindrical shouldered portions of the heads, and securing means extending through the annular disk portions of the heads into the

ends of the ribs, holding the heads and rim together in a unitary structure.

10. A rotary filing drum assembly comprising a stationary shaft, a one-piece, molded rim having an outwardly projecting card retaining rail, a clutch ring projecting into the interior of the rim, of increased thickness as compared to the remainder of the rim and shaped to provide on the inner surface thereof a plurality of radially extending pockets, a circumferential flange associated with said ring closing one end of each pocket, a plurality of spaced, inwardly projecting axially elongated ribs extending from the flange toward the other end of the rim, a drum head journalled on the shaft at one end of the rim connected to the ribs, and another drum head coaxial with the shaft at the other end connected to the ribs and closing the other ends of the pockets, a clutch core restrained against rotation on the shaft within the ring, and a roller disposed within each recess and confined therein by the flange and adjacent drum head, respectively, and engageable with the core.

11. A rotary filing drum assembly comprising a stationary shaft, a one-piece cylindrical rim member having an integral card retaining rail on its periphery and an integral, circumferentially extending, inwardly projecting ring in its interior, having outwardly extending radial pockets formed therein, open at one of their ends, and closed at the other, a pair of drum heads secured to the ends of the rim, one of said heads closing the open ends of the pockets, a clutch core restrained against rotation on the shaft within and opposite the ring and a plurality of clutch elements in said pockets making one-way clutch connection with the core.

12. A rotary filing drum assembly comprising a stationary shaft, a one-piece cylindrical rim member having an integral card retaining rail on its periphery and an integral, circumferentially extending, inwardly projecting ring in its interior, having outwardly extending radial pockets formed therein, open at one of their ends and closed at the other, a pair of drum heads secured to the ends of the rim, one of said heads closing the open ends of the pockets, a clutch core journalled for frictionally restrained rotation on said shaft within and opposite to said ring and having a plurality of inclined surfaces on its periphery, and a plurality of clutch elements in said pockets cooperating with the clutch core and making a one-way clutching engagement therewith.

13. A rotary filing drum assembly comprising a stationary shaft, a one-piece cylindrical rim member having an integral card retaining rail on its periphery and an integral, circumferentially extending, inwardly projecting ring in its interior, having outwardly extending radial pockets formed therein, open at one of their ends and closed at the other, a pair of drum heads secured to the ends of the rim, one of said heads closing the open ends of the pockets, a clutch core frictionally restrained against rotation on said shaft and positioned interiorly of the rim opposite said ring, said core having a

plurality of inclined surfaces on its periphery terminating at their radially inner ends in abutment shoulders, and rollers in each of said pockets, adapted to be projected into the pockets by said inclined surfaces upon rotation of the rim in one direction and to engage said abutment shoulders upon rotation in the other direction.

14. A rotary filing drum assembly comprising a stationary shaft, a one-piece, molded, plastic rim member having an integral card retaining rail on its periphery, a circumferential, inwardly projecting, integral clutch ring in its interior having outwardly extending radial pockets molded therein, open at their outer axial ends and closed at their inner axial ends, and a plurality of integral axially extending ribs running from the circumferential ring toward the opposite end of the rim, a pair of drum heads, one secured to the ring and closing the open ends of the pockets and the other secured to the ends of the ribs, a clutch core restrained against rotation on the shaft, inwardly of and aligned with the clutch ring, and means permitting rotation of the rim and ring in one direction relative to the core but preventing such relative rotation in the other.

15. A rotary filing drum assembly comprising a stationary shaft, a one-piece, molded, plastic rim member having an integral card-retaining rail on its periphery, a circumferential, inwardly projecting clutch ring in its interior spaced from the end of the rim a predetermined distance and having outwardly extending radial pockets open at their outer axial ends and closed at their inner axial ends, and a plurality of integral axially extending ribs running from the ring toward the remote end of the rim, and terminating in spaced relation therefrom a distance equal to said predetermined distance; a pair of drum heads journalled for rotation coaxially of the shaft, each comprising a central disk portion, a cylindrical shouldered portion having an axial length equal to said predetermined distance and a radially projecting peripheral flange, one of said heads being secured to the rim adjacent the ring, closing the open ends of the pockets and having the rim end seated upon the cylindrical shoulder thereof, the other head being secured to the rim adjacent the ends of the ribs, with the latter rim end seated upon the cylindrical shoulder thereof, a clutch core restrained against rotation on the shaft, inwardly of and aligned with the clutch ring, and means permitting rotation of the rim and ring in one direction relative to the core but preventing such relative rotation in the other.
